CONNECTER, PARTICULARLY FOR LAMPS
HAVING TWO FILAMENTS

James Tiburce Felix Conti, Paris, France

Application September 29, 1932, Serial No. 635,321
In France October 3, 1931

1 Claim. (Cl. 173—347)

This invention relates to switches which are interposed between a socket and a two filament lamp. Suggestions have already been made to use switches for bringing into circuit one or other of the two filaments of the lamp or the two filaments in parallel (maximum illumination) or the two filaments in series (dimming) or cutting both out (extinguishing).

The invention has for its object a switch which may be readily interposed between a socket having two contacts and the cap of a two filament lamp. This switch comprises a plug for engaging with the socket, this plug, provided with electric conductors, being connected to a sleeve provided with conducting blades and mounted on the cap of the two filament lamp. This sleeve is both capable of angular movement relatively to the plug out of axial movement for obtaining the various desired contacts between the conducting blades and the conductors of the plug and for facilitating the mounting of the plug in the socket, which is effected by the temporary locking of the sleeve to the plug.

The manner of carrying the invention into effect will be readily understood from the following description with reference to the accompanying drawing, wherein:—

Fig. 1 is a vertical section of the connector constructed for mounting on a socket with a bayonet joint and Fig. 2 is a section on the line A—A of Fig. 1.

Fig. 3 is a vertical section of the same connector arranged for mounting on a screwed socket.

Figs. 4 and 5 show respectively in elevation and in plan the framework of the connector shown in Fig. 1.

Figs. 6 and 7 show respectively a vertical section and a plan of a member of the connector.

Figs. 8 and 9 show in elevation and in plan the cap of a lamp having two filaments for use in connection with the connector.

Fig. 10, similar to Fig. 2, shows to a larger scale the contact blades and their connections to the two filaments of the lamp.

As shown in Fig. 1 the connector for direct application to a lamp is provided with a framework 1 of insulating material forming a plug of which the details are shown in Figs. 4 and 5. The upper portion of this framework is similar to the caps of lamps which fit into ordinary sockets. At its lower end it has a notched collar 2. Two contacts 3 and 4 are respectively secured to metal cups 5 and 6 in which are adapted to turn freely two metal balls 7 and 8.

The framework 1 is covered by a sleeve 9 having a rim which bears against the notched collar 2 of the framework.

A metal tube 10, shown in Figs. 6 and 7, is provided at its upper end with teeth 11 corresponding with and adapted to engage with the notches of the collar 2 in such a manner as to form a temporary connection between the tube 10 and the framework 1.

At the bottom the tube 10 is provided with 10 bayonet slots 12 adapted to receive the lamp. The tube 10 and the sleeve 9, which covers this tube, are connected together by a pin 13 which passes through the connector.

This pin engages with a groove 14 provided in 15 a washer 15 of insulating material, loosely located in the tube 10, which is provided with three blade contacts 16, 17, and 18 adapted to give passage to the current supplied by the balls 7 and 8 (Fig. 2). Underneath the blades are provided 20 seatings adapted to receive coiled springs 29. These springs respectively bear against each of the three blade contacts and are adapted to transmit the current to three contacts 20, 21 and 22 (Figs. 8 and 9) provided on the cap of a 25 lamp having two filaments.

Referring to Fig. 8 it will be seen that the two pins 23 and 24 are of different sizes so as to avoid any error in mounting as regards the position of the three contacts on the caps of the lamps having two filaments, whilst the slots 12 in the connector are also of different sizes corresponding with the pins.

In the device described it will be seen that the lamp and the sleeve 9 turn together around the 35 framework 1; it thus follows that for fitting the connector into the socket it is essential for the sleeve 9 and the framework 1 to be temporarily connected together. This result is obtained by the connecting device. It is sufficient for this 40 purpose to exert pressure on the sleeve 9 or the lamp so as to compress the three springs 29 and to bring the teeth 11 of the tube 10 into engagement with the notches of the collar 2 of the framework 1. The disengagement is effected 45 automatically under the action of the springs 29.

As will be seen in Fig. 10, showing the washer 15 and the contact blades 16, 17 and 18 to a larger scale, the various blades are provided with diametrically opposite grooves $a-a'$, $b-b'$, $c-c'$, $d-d'$, $e-e'$, the various diameters corresponding with two oppositely disposed grooves including between them an angle of 36° . These grooves are adapted to indicate the successive positions occupied by the balls which make the contacts. 55

It will also be seen that the edges at the adjacent faces of the blades 16 and 18 are bent upwardly and form the groove c' in such a manner that when one ball rests between these edges it connects the blades 16 and 18 electrically in parallel.

The lamp being fitted in position in the connector in the manner above described it is sufficient by acting either on the milled portion 19 of the sleeve 9 or on the lamp itself to turn the connecting pin 13 which by turning the washer 15 produces in succession the following lighting conditions, commencing from the extinguished condition:

a—a' extinguished condition, b—b' illumination of one filament, c—c' illumination of both filaments (the ball at c' bridging the two contact blades 16 and 18), d—d' illumination of the second filament, e—e' dimming (both filaments being in series).

20 Referring to Fig. 3 it will be seen that when the connector is adapted to be fitted into a screwed socket, only the framework 1 is modified. The notched collar 2 of the framework is in this case formed by a washer 25 suitably cut and held by a screw 26 under the framework. The cups 5 and 6 are respectively connected electrically to the screw thread 27 and to the central contact 28.

I claim:—

An adapter for connecting a two filament lamp having three contacts to a socket having two contacts, said adapter comprising a plug adapted to fit into said socket, two contacts in said plug, the contacts in said plug being adapted to cooperate with the contacts of said socket, a sleeve mounted for rotary and axial movement on said plug, an inner tube fixed to said sleeve, a washer loosely located in said tube, said washer having 1 a groove therein, a pin having its two ends secured to said tube and said sleeve and engaging with said groove, three spring blades carried by said washer, said spring blades being adapted to be brought selectively into operative contact with the contacts in said plug, three coiled springs carried by said washer, said coiled springs engaging with said spring blades and being adapted to co-operate with the contacts of said lamp, a notched collar on said plug, teeth on said tube 20 fixed to said sleeve, said teeth being adapted to be brought into operative engagement with said notched collar, said coiled springs serving to permit of temporary engagement of said teeth with said notched collar so as to facilitate the fitting 25 of the plug into said socket and to ensure contact between said spring blades and the contacts in said plug.

JAMES TIBURCE FELIX CONTI.
